UNITED STATES PATENT OFFICE

92,871

DESIGN FOR A CANOPY SUNSHADE

Rose Mary Stone, Toronto, Ontario, Canada

Application August 12, 1933, Serial No. 49,004
In Canada July 10, 1933

Term of patent 3½ years

To all whom it may concern:

Be it known that I, ROSE MARY STONE, a subject of the King of Great Britain, and resident of the city of Toronto, county of York, Province of Ontario, in the Dominion of Canada, have invented a new, original, and ornamental Design for a Canopy Sun Shade of which the following is a specification; reference being had to the accompanying drawing, forming part thereof.

The figure is a perspective view of the article showing my new design.

The design comprises a tilttable rectangular

awning supported centrally at each end by a double inverted V-shaped frame which straddles outwardly and the bottom ends are mounted upon large caster wheels, the tilttable awning being supported from two of its outside corners by spear-like rods which extend angularly inward and downward and are secured to the straddling end frames.

I claim:—

The ornamental design for a canopy sun shade as shown and described.

ROSE MARY STONE.
